CONVERTIBLE COLLAR AND YOKE FOR
LADIES' GARMENTS

Harry Metzger, Brooklyn, N. Y.

Application July 15, 1950, Serial No. 174,048

4 Claims. (Cl. 2—106)

This invention relates to a convertible collar and yoke for ladies' blouses and other wearing apparel and has for its principal object the provision of such a device that can readily be transformed from one stylish arrangement to another, thus providing a multi-purpose blouse, or garment.

Another object of the invention is the provision in the device of closing and connecting means which adapt the same to said variations in style or appearance.

Still another object of the invention is to construct the collar and yoke so that the same is capable of being manufactured and assembled in a lady's blouse or the like, economically.

For further comprehension of the invention, and of the objects and advantages thereof, reference will be had to the following description and accompanying drawings, and to the appended claims, in which the various novel features of the invention are more particularly set forth.

In the accompanying drawings forming a material part of this disclosure:

Fig. 1 is a front elevation of a blouse, incorporating the means of the invention.

Fig. 2 is a rear elevation of the blouse.

Fig. 3 is a detail view illustrating the pattern for the means of the invention.

Fig. 4 is a fragmentary enlarged sectional view on line 4—4 of Fig. 1.

Figs. 5 to 10 are fragmentary front views illustrating various arrangements of the convertible collar of the blouse.

Fig. 11 is a front elevational view similar to Fig. 1, but illustrating the blouse constructed in accordance with a modification of the present invention.

Fig. 12 is a rear elevational view of Fig. 11.

Fig. 13 is a plan view of a portion of Fig. 11.

Fig. 14 is a developed view of the blank used for making one-half of the collar and yoke used in the form of the invention shown in Figs. 11 to 13.

The convertible collar and yoke, according to the first form of the invention shown in Figs. 1 to 10, is shown applied to a blouse body 15 which for the purposes of the invention may be of any desired style and material, the only limitation being that the same must have a large neck opening 16.

According to the invention, a yoke 17 of material similar to or the same as that of the blouse, is secured at its outer perimetral edge to the edge of the neck opening 16 by stitching 18. At its front the yoke 17 is slit vertically from its

small neck opening 20 to the edge of the blouse neck opening 16, as at 21. At the upper end of said slit the material on either side thereof is extended to form a long tapering tail 22. Adjacent either edge of the slit 21 and also the under edge of each tail 22 there is provided a plurality of regularly spaced buttonholes 23. In the present instance three buttonholes are shown on either side of the slit and also three adjacent the lower edge of each tail.

According to the invention, the buttonholes are adapted to be interconnected by ordinary cuff links 24 as indicated in Fig. 1 or by a ribbon 25 as indicated in Fig. 10, in a variety of ways to 15 provide the blouse with a wide number of stylish collar and neckline appearances. A very large number of collar and neckline arrangements can be obtained by differentially connecting the buttonholes with the links 24 or the ribbon 25, but for 20 purposes of clarity only a few are illustrated herein.

In Fig. 5 the blouse is shown with the tails forming a collar and with the slit 21 completely open. Thus the plunging neckline style is obtained without utilizing the links 24 or the ribbon 25. The neckline can of course, be raised by utilizing one or more cuff links to close up the slit 21.

In Fig. 6 the blouse is shown in mandarin style, that is, with a high neckline and no collar. For this arrangement the tails 22 are extended downward within the blouse, and the slit 21 is completely closed by means of three cuff links 24.

In Fig. 7 the blouse is provided with a high neckline and with a small collar. This is achieved by folding the ends of tails 22 rearward under their bases and by using the cuff links to close slit 21.

In Fig. 8 the blouse has a high neckline and the tails 22 are crossed stylishly. The crossed tails are held in place by a cuff link 24 passed through a buttonhole 23 in each.

In Fig. 9 the slit 21 is partially open to provide an open neckline and the tails 22 are looped, being held in place each by a cuff link engaging the endmost buttonhole therein and also the adjacent top buttonhole at the side of slit 21.

In Fig. 10 the neckline is high and the tails 50 are brought together and extend downward, being held in place by a ribbon threaded through the several buttonholes therein and tied in a bow at the neck of the blouse.

It is believed that the few examples shown and 55 described serve to illustrate the versatility of

the means of the invention in transforming a blouse from one style and appearance to another simply and effectively.

In the modification of the invention shown in Figs. 11 to 14, the combined collar and yoke 17' of two part construction with each of the parts made of a blank 17^a similar to that shown in Fig. 14 but of opposite hand. Each of the blanks 17^a has a rearwardly projected extension 17^b with adjacent ends of the extensions being stitched together and to the top edges of the back portion of the blouse body 15. The straight edge 17^c of the main body of each of the blanks 17^a is stitched to the top edge of the back portion of the blouse body 15 to extend across the top of the shoulder, 15 as shown most clearly in Fig. 13.

In other respects, the form of the invention shown in Figs. 11 to 14 is similar to that illustrated in Figs. 1 to 10 and like reference numerals are used to identify like parts throughout the 20 several views.

It is to be understood that this combined collar and yoke arrangement may be used in any type and size of garment.

While I have illustrated and described the preferred embodiments of my invention, it is to be understood that I do not limit myself to the precise constructions herein disclosed and the right is reserved to all changes and modifications coming within the scope of the invention 30 as defined in the appended claims.

Having thus described my invention, what I claim as new, and desire to secure by United States Letters Patent is:

1. A convertible yoke and collar for a garment having a large neck opening, which comprises a fabric yoke having a small neck opening and secured at its perimetral edge to the edge of the neck opening of the garment, said yoke being slit in front from the neck opening therein to the edge of the neck opening in the garment, a long tapering tail extended from each edge of the slit at the upper end thereof, and a plurality of buttonholes arranged along each edge of the slit and also along the under edge of each tail. 35

2. A convertible yoke and collar for a garment having a large neck opening, which comprises a fabric yoke having a small neck opening and

secured at its perimetral edge to the edge of the neck opening of the garment, said yoke being slit in front from the neck opening therein to the edge of the neck opening in the garment, a long tapering tail extended from each edge of the slit at the upper end thereof, and a plurality of buttonholes arranged along each edge of the slit and also along the under edge of each tail, said fabric yoke being of one-piece construction.

3. A convertible yoke and collar for a garment having a large neck opening, which comprises a fabric yoke having a small neck opening and secured at its perimetral edge to the edge of the neck opening of the garment, said yoke being slit in front from the neck opening therein to the edge of the neck opening in the garment, a long tapering tail extended from each edge of the slit at the upper end thereof, and a plurality of buttonholes arranged along each edge of the slit and also along the under edge of each tail, said fabric yoke being of two-part construction.

4. A convertible yoke and collar for a garment having a large neck opening, which comprises a fabric yoke having a small neck opening and secured at its perimetral edge to the edge of the neck opening of the garment, said yoke being slit in front from the neck opening therein to the edge of the neck opening in the garment, a long tapering tail extended from each edge of the slit at the upper end thereof, and a plurality of buttonholes arranged along each edge of the slit and also along the under edge of each tail, said fabric yoke being of two-part construction, said two-part yoke having adjacent ends secured together at the back of the blouse.

HARRY METZGER.
